UNITED STATES PATENT OFFICE.

GEORGE F. MILLER, OF BROOKLYN, NEW YORK, ASSIGNOR TO AMERICAN CAN COMPANY, OF NEW YORK, N. Y., A CORPORATION OF NEW JERSEY.

SPRING-TOP POWDER-BOX.

No. 927,375.

Specification of Letters Patent.

Patented July 13, 1909.

Application filed October 26, 1908. Serial No. 459,474.

To all whom it may concern:

Be it known that I, GEORGE F. MILLER, a citizen of the United States, residing in Brooklyn, in the county of Kings and State 5 of New York, have invented a new and useful Improvement in Spring-Top Powder-Boxes, of which the following is a specification.

My invention relates to improvements in 10 tooth powder boxes or receptacles.

In the accompanying drawing forming a part of this specification, Figure 1 is a side elevation of a spring top tooth powder box or receptacle embodying my invention. Fig. 15 2 is a central vertical section on line 2—2 of Fig. 1. Fig. 3 is a cross section on line 3—3 of Fig. 2. Fig. 4 is a detail partial elevation and Fig. 5 is a detail partial sectional view showing a modification.

20 In the drawing, 1 represents a tooth powder box or other receptacle having a top 2, furnished with a neck 3, either integral with the top or in a separate piece and secured thereto as may be preferred. The neck 3 has an open upper end 4 and an aperture 5, 25 preferably located at its lower part, and a longitudinal extending guide or groove 6.

The closure sleeve or cap 7 fits inside the neck of the top and has a closed upper end 8 and an annular shoulder or enlargement 9 adapted to engage the open upper end of the neck 3 to limit the downward sliding movement of the cap or closure sleeve. The cap or closure sleeve is also provided with an 35 opening 10, adapted to register with the opening 5 in the neck 3 when the cap or closure sleeve is depressed. The cap or closure sleeve 7 is provided with a guide or projection 11, adapted to fit in the guide or groove 6 in the neck 3 to prevent the cap or closure sleeve from turning. The cap or closure sleeve 7 is provided at its lower end with a flange or shoulder 12 to limit its upward or outward sliding movement.

45 To automatically close the cap or closure sleeve 7 and hold it in its outermost position, the coiled spring 13 is inserted in the hollow cap or closure sleeve 7 and bears at its upper end against the closed upper end 8 of the sleeve 7, and this spring 13 is provided at its lower end with an extension 14, having a loop or bent arm 15 which is soldered or otherwise secured to the top 2 at 16, the extension 14 and bent arm 15 of the spring 55 fitting astride the lower end of the cap sleeve

7 when said sleeve is depressed so as not to interfere with the sliding movement of the sleeve in opening and closing.

In the modification illustrated in Figs. 4 and 5, the guide groove engaging the guide 60 device or projection 11 is made inclined or spiral instead of straight or longitudinal.

The spring 13 inside the cap or closure sleeve 7 is an open spiral one and serves by its expansion and contraction as a stirrer to 65 effectually prevent clogging of the sleeve or of its side dispensing aperture, as well as to restore said cap or closure sleeve to its closed position.

I claim:—

70

1. The combination with a tooth powder or other receptacle top having a neck open at its upper end, and provided with a dispensing aperture in its side, of a sliding cap or closure sleeve fitting inside said neck 75 and closed at its outer end and open at its inner end, and provided with a dispensing aperture in its side adapted to register with the dispensing aperture of the neck when the cap or closure sleeve is depressed, and 20 an open spiral spring inside said cap or closure sleeve to restore it to closed position and prevent clogging and bearing at its outer end against the closed outer end of said sleeve, said spring extending through 85 the open inner end of said cap and being attached at its inner end to said top, substantially as specified.

2. The combination with a tooth powder or other receptacle top having a neck open 90 at its upper end, and provided with a dispensing aperture in its side, of a sliding cap or closure sleeve fitting inside said neck and closed at its outer end and open at its inner end, and provided with a dispensing 95 aperture in its side adapted to register with the dispensing aperture of the neck when the cap or closure sleeve is depressed, and an open spiral spring inside said cap or closure sleeve to restore it to closed position 100 and prevent clogging and bearing at its outer end against the closed outer end of said sleeve, said spring extending through the open inner end of said cap and being attached at its inner end to said top, said 105 cap or closure sleeve having a stop flange or shoulder at its lower end to limit the outward movement thereof, substantially as specified.

3. The combination with a tooth powder 110

or other receptacle top having a neck open at its upper end, and provided with a dispensing aperture in its side, of a sliding cap or closure sleeve fitting inside said neck and closed at its outer end and open at its inner end, and provided with a dispensing aperture in its side adapted to register with the dispensing aperture of the neck when the cap or closure sleeve is depressed, and an open spiral spring inside said cap or closure sleeve to restore it to closed position and prevent clogging and bearing at its outer end against the closed outer end of said sleeve, said spring extending through the open inner end of said cap and being attached at its inner end to said top, said cap or closure sleeve having a stop flange or shoulder at its lower end to limit the outward movement thereof, and said cap or closure sleeve having at its outer end a shoulder to limit the inward movement thereof by engagement with the open outer end of said neck, substantially as specified.

4. The combination with a tooth powder or other receptacle top having a neck open at its upper end, and provided with a dispensing aperture in its side, of a sliding cap or closure sleeve fitting inside said neck and closed at its outer end and open at its inner end, and provided with a dispensing aperture in its side adapted to register with the dispensing aperture of the neck when the cap or closure sleeve is depressed, and an open spiral spring inside said cap or closure sleeve to restore it to closed position and prevent clogging and bearing at its outer end against the closed outer end of said sleeve, said spring extending through

the open inner end of said cap and being attached at its inner end to said top, said neck and said cap or closure sleeve having inter-engaging guides to prevent the cap or closure sleeve from turning, substantially as specified.

5. The combination with a receptacle top having a neck furnished with a dispensing aperture in its side, of a hollow sliding cap open at its inner end and closed at its outer end and furnished with a dispensing aperture in its side and an open spiral spring inside said cap to restore it to closed position and prevent clogging and bearing at its outer end against the closed outer end of said cap said spring extending through the open inner end of said cap and engaging at its inner end said top, substantially as specified.

6. The combination with a receptacle top having a neck furnished with a dispensing aperture in its side, of a hollow sliding cap open at its inner end and closed at its outer end and furnished with a dispensing aperture in its side, and an open spiral spring inside said cap to restore it to closed position and prevent clogging and bearing at its outer end against the closed outer end of said cap said spring extending through the open inner end of said cap and engaging at its inner end said top, substantially as specified.
